UNITED STATES PATENT OFFICE.

WILLIAM N. HUNTER, OF BLANCHESTER, OHIO.

RECEIVER.

Application filed December 11, 1925. Serial No. 74,829.

My invention relates generally to receivers or instruments for intensifying sounds such as telephones and radio loud speakers, and particularly to novel resilient 5 diaphragm mountings for such instruments.

In telephone and radio receivers whether they be used in plain or radio telephony magnetic coils are usually disposed within the instruments, the cores of which 10 extend beyond the planes of the ends of the coils. A flexible resilient diaphragm of some magnetic material is disposed in close proximity to the magnetized cores. Audio frequency electrical vibrations passing 15 through the coils cause the diaphragm to vibrate and the diaphragm acting as a drum head produces sound waves. The fact that the transmitters and receivers are constructed on similar principles and operate, 20 one the reverse of the other, is well known and requires no further elaboration.

It is particularly my object to provide a vibratory diaphragm which will not be affected by chance vibrations of the instrument 25 itself which impair the clear tone of the sound waves and to this end it is my purpose to provide diaphragms comprising magnetic discs with mounting rings of shock absorbing material such as vulcanized 30 rubber by which the discs may be held in proper position with relation to the cores of the coils in the instrument, without the disc being clamped against any rigid parts of the instrument. It is further my object to 35 vulcanize the mounting rings integrally with the discs so that the discs and mounting rings may be provided as integral members.

Referring to the drawing in which I have 40 illustrated my invention as applied to a radio loud speaker:

Figure 1 is a plan view of my magnetic disc prior to its being vulcanized to the mounting members.

45 Figure 2 is a section through one of the diaphragms ready for insertion into the receiver.

Figure 3 is a section of one type of receiver showing the diaphragm in operative 50 position.

I have shown a magnetic disc 1 which has

its outer periphery close to the edges perforated with holes 2. A rubber ring 3 having a peripheral slot 4 is then provided and the disc inserted into the slot. 55

The rubber is then vulcanized and flows within the holes 2, as indicated at 3^a, with a result that a diaphragm member is provided consisting of the central disc portion and the annular mounting members integrally vulcanized to the disc and so supporting the disc that the outer edges thereof are completely enclosed in the rubber. I have further found that a coating of beeswax 4^a at the juncture of the ring 3 and the disc 65 1 seems to prevent the ring 3 from interfering with the free vibration of the disc 1 and to improve the vibratory tone of the disc. The receiver illustrated comprises the casing 5 within which the coils 6 are connected with the wires 7. The casing has a central aperture 8 to allow for the insertion of a loud speaker horn and a downwardly flanged annular wall 9, preferably with internal threads for securing the cover 10 70 of the container within which the coils or diaphragm are mounted. The cover also has a central aperture 10^a. The receiver casing 11 has an adjustment thumb screw 12 which regulates the distance between the 75 magnetic cores 13 and the diaphragm 1.

The diaphragm 1 supported by the annular ring 3 is disposed with the ring retained between the annular walls of the box and the inner side of the cover. The receiver casing has preferably external threads 85 14 which engage internal threads 15 of the cover member. By rotating the box within the cover any desired clamping force may be obtained on the ring 3 to hold it in position. 90

Although I have shown a receiver with a single diaphragm, it should be understood that my invention does not relate to any particular type of receiver, but specifically relates to the mounting of the magnetic diaphragm and I consider the use of any shock absorbing material which is molded or vulcanized about a magnetic disc so as to completely insulate the outer periphery of the disc from local vibrations, well within the 95 range of mechanical equivalents. 100

Having thus described my invention, what I claim as new and desire to secure by Letters Patent, is:—

In a receiver, a recessed magnetic disc having an annular shock absorbing ring member enclosing said disc and integral portions of said ring member extending with-

in said recesses to retain said disc in a complete shock resistant position, and a sealing coating of material formed over the peripheral juncture of said disc and said enclosing ring member. ¹⁰
